MULTIPLE SEATING UNIT

George Kasparian, 9562 La Tijera Blvd.,
Los Angeles, Calif.

Filed July 5, 1960, Ser. No. 61,207

Term of patent 14 years

(Cl. D15—11)

Fig. 4

I claim:

The ornamental design for a multiple seating unit, as shown.
